UNITED STATES PATENT OFFICE.

GEORGE ROTUS EVERSON, OF CINCINNATI, OHIO.

DESIGN FOR A BIBLICAL INDEX.

Application filed October 25, 1922. Serial No. 4,080. Term of patent 7 years.

To all whom it may concern:

Be it known that GEORGE ROTUS EVERSON, a citizen of the United States, residing at Cincinnati, in the county of Hamilton and State of Ohio, has invented a new, original, and ornamental Design for a Biblical Index, of which the following is a specification, reference being had to the accompanying drawings, forming part thereof.

The figure is a plan view of the Biblical index constituting my new ornamental design.

Having described my invention, what I claim as new and useful and desire to secure by Letters Patent, is:—

The ornamental design for a Biblical index, as herein shown.

In testimony whereof I have hereunto set my hand in presence of two subscribing witnesses.

GEORGE ROTUS EVERSON.
